US0D1034696S

(12) **United States Design Patent** (10) **Patent No.:** **US D1,034,696 S**
(45) **Date of Patent:** **** Jul. 9, 2024**

(54) **ELECTRONIC PLAYER**

(71) Applicant: **Shenzhen Little Magic Technology Co., Ltd.**, Shenzhen (CN)

(72) Inventor: **Fei Mao**, Shenzhen (CN)

(73) Assignee: **Shenzhen Little Magic Technology Co., Ltd.**, Shenzhen (CN)

(**) Term: **15 Years**

(21) Appl. No.: **29/838,911**

(22) Filed: **May 17, 2022**

(30) **Foreign Application Priority Data**

May 10, 2022 (EM) 009020134-0001

(51) **LOC (14) Cl.** **14-01**

(52) **U.S. Cl.**

USPC **D14/203.1; D14/496**

(57) **CLAIM**

The ornamental design for an electronic player, as shown and described.

DESCRIPTION

FIG. 1 is a front perspective view of an electronic player showing my new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an enlarged detail view of the indicated portion 9 in FIG. 1; and,

FIG. 10 is an enlarged detail view of the indicated portion 10 in FIG. 2.

The broken lines shown in the drawings depict portions of the electronic player that form no part of the claimed design. The long dash short dash broken lines indicate boundaries for enlarged detail portion views and form no part of the claim.

1 Claim, 10 Drawing Sheets
